(57) **CLAIM**

The ornamental design for a lid for bottle, as shown and described.

DESCRIPTION

FIG. 1 is a perspective view of the lid for bottle;

FIG. 2 is a front view of the lid for bottle;

FIG. 3 is a left side view of the lid for bottle;

FIG. 4 is a right side view of the lid for bottle;

FIG. 5 is a top view of the lid for bottle;

FIG. 6 is a bottom side view of the lid for bottle; and,

FIG. 7 is a rear view of the lid for bottle; bottle.

The broken lines in the drawings are included for the purpose of illustrating the lid in positions of use with the environment of a bottle that forms no part of the claimed design.

1 Claim, 6 Drawing Sheets
